UNITED STATES PATENT OFFICE.

THOMAS NATHAN RUSSELL, OF CHICAGO, ILLINOIS, ASSIGNOR TO CHICAGO-CLEVELAND CAR ROOFING CO., OF CHICAGO, ILLINOIS, A CORPORATION OF ILLINOIS.

CAR-ROOF.

1,342,510.

Specification of Letters Patent.

Patented June 8, 1920.

Application filed August 18, 1915. Serial No. 46,076.

To all whom it may concern:

Be it known that I, THOMAS NATHAN RUSSELL, a citizen of the United States, residing in Chicago, in the county of Cook and State of Illinois, have invented a new and useful Improvement in Car-Roofs, of which the following is a specification.

The invention relates to outside car roofs and has for its objects certain improvements in the roof set forth in my application No. 19,902, filed April 8, 1915. These improvements relate more particularly to the combination, with the said structure of roof, of a ridge pole and purlins and filler bars in the same arranged to carry the bodies of the roof sheets at a distance above the carline flanges, so that the depth of the roof sheet seam flanges and seams are reduced and the sheets strongly supported throughout. By this construction roof sheets of lighter metal are rendered efficient. I also simplify the formation of the seam flanges of the roof sheets, carrying them down vertically upon the outer sides of the side plates, and closing and supporting them by filler castings. This construction allows the carlines to be shortened and simplified, and they terminate on the tops of the side plates, without depending flanges; the roof sheets being strongly united with the carlines by double seam flanges which are of arched formation and spaced apart, and the strong connection of the said flanges in arched or U-form with the vertical face of the side plate being sufficient to take the place of such connection of the carlines. The improvements also relate to such other features of advantage as are inherent in the construction about to be described.

With such objects in view, the invention consists in the parts and combinations thereof herein set forth and claimed.

I order to make the invention more clearly understood I have shown in the accompanying drawings means for carrying the same into practical effect, without limiting my improvements, in their useful applications, to the particular construction which, for the purpose of explanation, I have made the subject of illustration.

In said drawings—

Figure 1 is a top plan view of a car roof embodying the invention, portions of the same being broken away.

Fig. 2 is a side view of the same.

Fig. 3 is a vertical cross section of a portion of the same, on a larger scale.

Fig. 4 is a vertical, central longitudinal section, at the ridge, of an end portion of the roof.

Fig. 5 is a vertical cross section of the ridge portion on a still larger scale.

Fig. 6 is a longitudinal section at the ridge, across one of the carlines.

Fig. 7 is a plan view of one of the car- 65 lines.

Fig. 8 is a side view of the same.

Fig. 9 is a vertical section, longitudinally of the car, of an intermediate roof sheet and an end roof sheet, the middle portions of 70 the said sheets being broken away.

Fig. 10 is a vertical cross section of the eaves portion of the roof.

Fig. 11 is a vertical, section of one of the carline bolts.

Figs. 12 and 13 show an inner face view and a vertical section of the filler casting for the vertical parts of the roof sheet seams.

Referring to the drawings, the upper part 80 of the car body frame, which is the supporting frame for the roof, comprises side plates of Z-bar cross section, each side plate consisting of a vertical longitudinal web 1, an inwardly extending top horizontal flange 2 85 and an outwardly extending bottom horizontal flange 3, the latter acting as a substitute for a fascia for protecting the eaves portions of the roof, especially the project-arched roof sheet seams. These side plates 90 are united at the ends of the car by end plates 4 of suitable character, preferably of the form shown, which are arched from side plate to side plate across the car and comprise an arched flange 5 extending inwardly 95 from the end of the car and terminating in horizontal flanges 6 which rest on and are riveted to the top side plate flanges 2. The flange 5 is in line with and conforms to the bottom flanges of the carlines.

The end plate also comprises a vertical end portion 7 which is flush with the end sheathing 8 (Fig. 4), said end portion terminating in an outwardly extending flange 9 which is level with the bottom side plate 105 flanges 3. The side plates and end plates are supported by suitable posts 10 and braces 11, which rise from the sills (not shown) and are united with the flanges 3 and 9 by brackets 12. The said end sheathing and the 110

side sheathing 13 are attached to the inner sides of the upright members of the car body frame, and extend up against the inner faces of the side plate webs 1 and of the 5 end plate member 7.

At suitable intervals along the side plates are arranged carlines 14 which are arched across the ridge, from side plate to side plate. Each carline has in cross section the 10 form of an inverted channel bar of U or trough-like shape (Fig. 6) having vertical webs or flanges 15, a connecting top web 16 and outwardly extending bottom side flanges 17. The ends of the carline are formed with 15 horizontal flanges 18, which are continuations of the flanges 17, and which rest on the side plate flanges 2 (Fig. 10), the carline terminating at about the vertical planes of the side plate webs 1. The flanges 18 20 may be extended or spread longitudinally of the car as seen in Fig. 7.

The carline is or may be die-formed of one integral piece of heavy sheet metal, being pressed into the permanent form shown. 25 The flanges 18 are perforated at 19 for riveting to the side plate flanges 2 at 20. The side flanges of the carline are perforated at 21 for the attachment of the longitudinal roof frame members, and the webs 16 at 22 for 30 the attachment of the roof sheets.

The roof frame also comprises longitudinal frame members, consisting of a ridge pole 23 and purlins 24. Or the ridge pole 23 may be omitted and more purlins added. 35 These members are in the form of U-channel bars with horizontal side flanges 25. These flanges are applied to the under sides of the carlines and are riveted at 26 to the side flanges 17 of the carlines through the perforations 21. In the channels of these members 23, 24 are fitted filler bars 27 of wood (which may be about two by two and a half inches in cross section) which extend from carline to carline (see Figs. 5 and 6). These 40 bars extend about half way up the sides of the carlines and there carry the bodies of the roof sheets 28, thereby diminishing the vertical dimension of the roof sheet seams while allowing to the carline the depth necessary for strength and stiffness. The bars 27 45 may be notched at 29 so that their lower parts abut the flanges 17 and their upper parts extend to the webs 15.

The roof sheets 28 (Fig. 9) are formed at 50 their side edges with seam flanges comprising preferably vertical flanges 30 which are or may be in contact with the sides of the vertical carline webs 15, and these flanges are continued into horizontal flanges 31 55 which overlie the horizontal top webs 16 of the carlines. The flange 31 at one edge of the sheet is immediately next to the carline, and terminates in an upturned supporting and water excluding lip 32. The upper and 60 outer flange 31 terminates in a downwardly

extending flange 33, and a horizontal lip 34 which rests on the top of the next roof sheet. The flanges 30, 31, 33 of the exterior overlapping roof sheet edge thus constitute a water tight seam cap. The outer flange 31 is 70 strongly supported by collars 35 which are integral with the carline bolts 36 (Figs. 6 and 11), and the head portion 37 of such bolt, before it is headed, is passed up through a perforation 38 in the flange 31, and is there 75 riveted down into a head 39. The lower threaded part of the bolt passes down through a perforation 40 (Fig. 9) in the lower and inclosed flange 31 of the next roof sheet, and then through a perforation 22 of 80 the carline, and there receives a nut 41 which is arranged in the channel of the carline. Nut locks 42 are preferably used with the nuts 41. The seam portions of the two meeting roof sheets are thus spaced part, and 85 both are rigidly and independently united with the carline, forming a strong and braced seam and cap. I prefer to employ four of the bolts 36 along the arch of the carline, at the places indicated by the perforations 22 in Fig. 7. The two bolts near and at each side of the ridge also embrace the saddle 43 for the running boards 44 (Fig. 6), said saddle being thereby bolted down on the seam cap portions of the roof 90 sheets. One edge of the saddle 43 is curved to conform to the arch of the seam (Fig. 3) and the other side is flat and horizontal and on the latter side the boards are secured by bolts 45. The heads of those bolts 36 which do not include the saddle, rest directly on the 95 seam flange 31.

The end roof sheets 46 terminate at one edge in a depending flange 47, and at the other edge one of them terminates in a lip 32 105 and the other in a flange 33 and lip 34. Each of these end roof sheets is supported at the end of the car by a fascia 48 bolted to the end plate 4 so as to extend above the flange 5 and be flush with the tops of the filler 110 bars 27.

The filler casting 49 for the depending portions of the seams is shown in Figs. 12 and 13. It is of a shape and size to fit within the flanges 30, 30, 31; that is to say it corresponds with the carline webs 15, 15, 16. It is perforated at 50 to receive a through bolt 51 which passes from the outside of the flange 31 to the inside of the side plate web 1 (Fig. 10). This casting is preferably 115 cored out as indicated to lighten it.

The depending eaves portions of the roof sheets between the seams are secured to the side plates by bolts 52.

What is claimed is:—

1. In a car roof, in combination: a roof frame comprising side plates, carlines arched from side plate to side plate channeled on their under sides and formed with lateral bottom flanges, and a ridge pole and purlins 130

- beneath the carlines channeled on their upper sides and having lateral top flanges; means for uniting said flanges of the ridge pole and purlins with the flanges of the carlines; roof sheets formed with seam flanges inclosing the tops and a part of the sides of the carlines, one of the two meeting roof sheets having a side flange and a top flange and the other sheet having two side flanges 5
- 10 and a top flange forming a cap inclosing the said flanges of the first mentioned sheet, and said top flanges being rigidly spaced apart one above the other and both bolted to the top web of the carline; and filler bars in the 15 channels of the ridge pole and purlins and supporting the bodies of the roof sheets between the carlines, said filler bars extending up to points above the bottoms of the carlines and below the tops of the seam flanges 20 of the roof sheets.
2. In a car roof, in combination: a roof frame comprising side plates, carlines arched from side plate to side plate channeled on their under sides and formed with lateral 25 bottom flanges and terminating on and bolted to the tops of the side plates, and a ridge pole and purlins beneath the carlines channeled on their upper sides and having lateral top flanges; means for uniting said 30 flanges of the ridge pole and purlins with the flanges of the carlines; roof sheets formed with seam flanges inclosing the tops and a part of the sides of the carlines, and depending down on the outer sides of the 35 side plates; filler castings in the depending parts of the seam flanges beyond the terminations of the carlines; bolts securing rigidly together the seam flanges, filler castings and side plates; and filler bars in the 40 channels of the ridge pole and purlins and supporting the bodies of the roof sheets between the carlines, said filler bars extending up to points above the bottoms of the carlines and below the tops of the seam 45 flanges of the roof sheets.
3. In a car roof, in combination: a roof frame comprising side plates, carlines arched from side plate to side plate and channeled on their under sides and formed with lateral bottom flanges seated on and secured to the 50 tops of the side plates, roof sheets having edge flanges bent to inclose said carlines, the eaves ends of said flanges extending down at the outer sides of the side plates, 55 filler castings for the vertical end portions of the roof sheet flanges adapted to be bolted with said flanges to the outer faces of the side plates in line with the carline channels, and bolts passing through the ends of the roof sheets and said castings and 60 the side plates.
4. In a roof sheet, in combination: arched carlines channeled on their under sides and formed with lateral bottom flanges; roof sheets formed with seam flanges inclosing 65 the tops and a part of the sides of the carlines, one of the two meeting roof sheets having a side flange and a top flange and the other sheet having two side flanges and a top flange forming a cap inclosing the said 70 flanges of the first mentioned sheet, and said top flanges being rigidly spaced apart one above the other and both bolted to the top web of the carline.
5. In a car roof, in combination, arched 75 carlines of inverted U-shape forming channels on their under sides and formed with horizontal side flanges, purlins of U-shape and having channels on their upper sides and horizontal side flanges, filler bars seated in 80 the channels of the purlins and extending above the side flanges of the carlines, means for securing together the said flanges of the purlins and carlines, and roof sheets having bent side edges channeled to inclose the 85 carlines, the main portions of the roof sheets being supported by said filler bars.

In testimony whereof I affix my signature hereto.

THOMAS NATHAN RUSSELL.
